Des. 176,334
Patented Dec. 13, 1955

176,334

AUTOMOBILE TRAILER

John Curtis Holmes, Chattanooga, Tenn.

Application March 30, 1954, Serial No. 29,772

Term of patent 14 years

(Cl. D14—3)

Fig. 2.

Fig. 1.

Fig. 3.

Fig. 4.

Figure 1 is a perspective view of an automobile trailer embodying my new design, as seen from one side thereof;

Figure 2 is a perspective view of a trailer embodying my new design, as seen from the opposite side of the same;

Figure 3 is a top plan view of the trailer embodying my new design; and

Figure 4 is a rear elevation thereof.

I claim:

The ornamental design for an automobile trailer, as shown.
